G. P. MUNDY.
TELEPHONE ATTACHMENT.
APPLICATION FILED MAR. 6, 1915.

1,171,745.

Patented Feb. 15, 1916.

UNITED STATES PATENT OFFICE.

GEORGE P. MUNDY, OF WASHINGTON, DISTRICT OF COLUMBIA.

TELEPHONE ATTACHMENT.

1,171,745.

Specification of Letters Patent. Patented Feb. 15, 1916.

Application filed March 6, 1915. Serial No. 12,492.

To all whom it may concern:

Be it known that I, GEORGE P. MUNDY, a citizen of the United States, residing at Washington, in the District of Columbia, 5 have invented certain new and useful Improvements in Telephone Attachments, of which the following is a specification.

My invention relates to improvements in telephone attachments.

10 The object of my invention is to provide an attachment for a desk telephone which is adapted to wind up the cord carrying the wires leading to the telephone and at all times keep it in a taut position in respect 15 to its connection with the box always employed in telephones.

Another object of my invention is to provide an attachment of this character which will not have a tendency to move the telephone from its placed position and yet will at all times keep the cord comparatively taut.

20 Another object of my invention is to provide an attachment of this character which can be readily applied to the ordinary telephone and which does not disfigure the telephone and at the same time provides an attachment having certain details of construction and operation hereinafter more fully described.

25 In the accompanying drawings,—Figure 1 is a perspective view of a telephone with my attachment applied and resting upon a desk showing the cord held taut and showing in dotted lines the telephone in a different position on the desk; Fig. 2 is an enlarged vertical sectional view of the base of a telephone, showing my attachment applied thereto; and Fig. 3 is a perspective view of my attachment showing the parts in 30 their disassembled relation.

Referring now to the drawings, 1 represents the ordinary telephone which, as shown, is of the desk form, and needs no further description. The base 2 is of an 35 enlarged form and is provided with an opening 3 through which the wires or cord leading to the transmitter and also to the box carrying the bells, pass. In telephones

of this character it is necessary to have a sufficient amount of cord leading from the 50 base of the telephone to the box to allow the telephone to be used from any point on the desk. This large amount of cord is greatly in the way and especially when the telephone is on the desk at a point close to the 55 bell box.

In my improved attachment, as heretofore stated, the base 2 of the telephone 1, is of an enlarged form and has a downwardly extending flange 4, in which is secured the base 60 plate of the ordinary telephone. In my improved attachment, the base plate of the ordinary telephone is removed and has secured within the upper end of the base 2 a circular member 5. This circular 65 member 5 is secured within the base 2 by means of screws 6 and is provided with downwardly extending integral legs 7, to which are secured, by means of screws 8, a disk 9 which is of a diameter approximately that of the interior of the base 2. Secured within the telephone above the member 5 is a downwardly extending arm 10, which has its lower end turned laterally 70 at 11, and is provided with an opening 12. 75 The arm 10 is of such a length that the laterally turned portion thereof rests upon the upper face of the disk 9.

Passing downwardly through the opening 12 in the arm 10, and also through an opening 13 in the disk 9, is a bolt 14, which forms the bearing for the reel 15. This reel 15 is preferably constructed of a block of wood 16, and has metal plates 17 arranged on each side thereof and extend outwardly beyond 80 the block of wood 16 to a point close to the inner periphery of the base 2. The space between the plates 17 is approximately equal to the diameter of the cord 18 which leads to the box 19 carried by the desk 20. The 85 upper face of the outer plate 17 has secured thereto a drum 21, which has an opening therethrough, through which the bolt 14 passes and the said bolt also passes through the plate 17 and the block 16. The lower 90 end of the bolt 14, below the lower plate 17,

has screwed thereon the nuts 22 and 23, whereby the reel formed by the block 16 and plate 17 are held thereon, but are free to rotate.

5 Secured to the lower face of the bottom plate 17 is the inner end of the coil spring 24. This connection between the spring 24 and the reel is by means of a staple 25. The outer end of the coil spring 24 is secured to 10 the plate 26 and forms the base of the telephone taking the place of the usual base now used. This connection between the outer end of the spring and the plate 26 is made by striking the metal of the plate upwardly, as 15 indicated at 27, and passing the wire loop 28 therethrough so as to secure the said loop to the plate, and the said loop in turn is secured to the free end of the coil spring. The center of the plate 26 is provided with a central upwardly pressed portion 29, having an 20 opening in its center through which the bolt 14 passes. Screwed upon the outer end of the bolt, on the outside of the plate 26, is a nut 30, by means of which the plate is secured to the bolt. The outer end of the plate 25 26 is provided with an upwardly turned flange 31, and resting on the said plate on the inside of the flange is a cylindrical shaped member 32. The upper end of this 30 member 32 enters the base 2 of the telephone on the inside of the flange 4. By this arrangement, it will be seen that the entire reel, spring and other parts of the attachment are wholly inclosed within the base 35 and forms a very neat appearance only adding about an inch and a quarter to the height of the telephone. The cylindrical member 32, at one side is provided with an opening 33 having a spun portion 34 there- 40 around which forms means for allowing the cord to freely pass through the opening without injury thereto. The cylindrical member 32 is clamped to the base by means of the plate 26 and the nut 30, as clearly 45 shown in Fig. 2 of the drawing.

The cord 18 passes from the block 16 through the opening 33 and is wound upon the block 16 between the plates 17. The inner end of the cord passes through an 50 opening 35 in the upper plate 17 and is coiled upon the drum 21, and passes upwardly through an opening 36 in the plate 9 and then upwardly to the telephone in the usual manner. In Fig. 2, it will be seen that 55 there are the same number of coils of the cord between the plates 17 as are arranged on the drum 21 and thus, as the drum is unwound, the cord unwinds therefrom. The relative size of the drum 14 and the block 16 60 allows enough cord to be withdrawn from the base of the telephone to enable the use of the phone at any point on the desk.

When more cord is necessary an extra coil is made upon the drum 14 and also upon the block 16. The spring 24, as will be readily understood, rotates the reel so as to cause a constant tension upon the cord 18. The tension of this spring is only sufficient to wind the cord, but not to disturb the position of the telephone on the desk or other support 70 upon which it is used. When the tension of the spring 24 is not sufficient to wind the cord, the nut 30 is loosened and the plate 26 is turned and having one end of the coil spring attached thereto, it will be seen that 75 the spring is wound in respect to the reel to which the other end of the spring is attached. The lower face of the plate 26 is practically covered with felt like the bottom plate of the ordinary telephone. 80

Having thus described my invention, what I claim as new and desire to secure by Letters Patent, is:—

1. The combination with the base of a desk telephone, of a cylindrical member 85 within the base and extending below the same, a rotatable plate closing the lower end of the cylindrical member, a reel within the cylindrical member and upon which is wound the cord leading from the telephone 90 to the bell-box, a spring having one end secured to the reel and the opposite end to the plate.

2. The combination with a desk telephone, 95 of a cylindrical member secured to the lower end and forming the base, of a spring wound reel within the cylindrical member, and having a drum on its upper face, the cord carrying the wires leading from the telephone wound upon the drum and passing to the 100 center of the reel and wound thereon and passing outwardly to the bell box, whereby a constant tension is kept on the cord between the bell box and the telephone.

3. The combination with a desk telephone, 105 of a cylindrical member secured to the lower end thereof and forming the base, of a spring wound reel within the cylindrical member, and a drum carried by the upper 110 face of the reel and upon which is coiled the 115 cord leading from the phone and carrying the wires, said cord passing from the drum to the inner periphery of the reel and wound thereon and passing outwardly through an opening in the cylindrical member, whereby a constant tension is kept on the cord between the bell box and the telephone.

4. The combination with a desk telephone having a cylindrical member secured to the 120 lower end thereof and forming the base of the telephone, a horizontally arranged reel within the cylindrical member, a spring for winding the reel and having one end con-

ected to the cylindrical member, the upper end of the reel having a drum secured thereto and upon which is wound the cord carrying the wires from the phone and 3 said cord passing from the drum to the inner periphery of the reel and wound thereon and passing outwardly through the cylindrical member, whereby a constant tension

is kept upon the cord between the telephone and the bell box.

In testimony whereof I affix my signature in presence of two witnesses.

GEORGE P. MUNDY.
